UNITED STATES PATENT OFFICE

ELUE O. FRITCH, OF CUMBERLAND, MARYLAND, ASSIGNOR TO THE KELLY-SPRING-FIELD TIRE COMPANY, OF CUMBERLAND, MARYLAND, A CORPORATION OF NEW JERSEY

DESIGN FOR A VEHICLE TIRE

Application filed January 14, 1933. Serial No. 46,829. Term of patent 14 years.

To all whom it may concern:

Be it known that I, ELUE O. FRITCH, a citizen of the United States, residing at Cumberland, in the county of Allegany and State of Maryland, have invented a new, original, and ornamental Design for a Vehicle Tire, of which the following is a specification, reference being had to the accompanying drawing, forming a part hereof.

Figure I is a perspective view of a fragment of the tire showing the design.

Figure II is a transverse cross-sectional view through the tire of Figure I.

I claim:

The ornamental design for a vehicle tire as shown.

ELUE O. FRITCH.
